UNITED STATES PATENT OFFICE.

LOUIS M. HOOPER, OF RUTHERFORD, NEW JERSEY, ASSIGNOR TO THE J. L. MOTT IRON WORKS, OF NEW YORK, N. Y., A CORPORATION OF NEW YORK.

DESIGN FOR A HOLDER FOR TUMBLERS OR SIMILAR VESSELS.

SPECIFICATION forming part of Design No. 35,245, dated October 29, 1901.

Application filed March 28, 1901. Serial No. 53,358. Term of patent 14 years.

To all whom it may concern:

Be it known that I, LOUIS M. HOOPER, a citizen of the United States, residing at Rutherford, in the county of Bergen and State of New Jersey, have invented and produced a new and original Design for a Holder for Tumblers and Similar Vessels, of which the following is a specification, reference being had to the accompanying drawings, forming part thereof.

Figure 1 is a side elevation of my fixture, and Fig. 2 is a perspective thereof.

As shown in the drawings, the leading or material feature of my design consists of a series of spring-arms A, radiating from a center piece B and curving upward and inward so as to engage a tumbler or other vessel which may be placed therein, the upper ends or tips

of the arms curving outward and the whole supported by an arm extending from the bottom of the center piece. The center piece is shown as supported upon an arm C, which is designed to be secured to any convenient base.

Having described my invention, what I claim as new, and desire to secure by Letters Patent, is—

The design for a holder for tumblers and similar vessels, substantially as herein shown and described.

L. M. HOOPER.
